UNITED STATES PATENT OFFICE.

MILLARD J. COLE, OF POTTERSDALE, PENNSYLVANIA.

STAIR-CARPET FASTENER.

1,284,244.

Specification of Letters Patent. Patented Nov. 12, 1918.

Application filed June 10, 1918. Serial No. 239,160.

To all whom it may concern:

Be it known that I, MILLARD J. COLE, a citizen of the United States, residing at Pottersdale, in the county of Clearfield, State 5 of Pennsylvania, have invented certain new and useful Improvements in Stair-Carpet Fasteners; and I do hereby declare the following to be a full, clear, and exact description of the invention, such as will enable 10 others skilled in the art to which it appertains to make and use the same.

This invention relates to new and useful improvements in carpet fasteners and particularly to devices for holding stair carpet.

15 One object of the present invention is to provide a novel and improved device of this character which is especially adapted to hold stair carpet in proper position without the use of tacks.

20 Another object is to provide a novel and improved device of this character by means of which the carpet can be held in proper and smooth condition and which is easily and quickly operated to apply to the carpet 25 or release therefrom to permit the carpet to be taken up.

Other objects and advantages will be apparent from the following description when taken in connection with the accompanying 30 drawing.

In the drawing:

Figure 1 is a perspective view of a portion of a stairway showing my invention attached to the wall at one end of the step.

35 Fig. 2 is a similar perspective view showing the invention attached to the tread of the step.

Fig. 3 is a similar view showing the device attached to the riser of the step above.

40 Fig. 4 is an enlarged vertical transverse sectional view through the device removed from the step.

Fig. 5 is a perspective view of one of the members of the device.

45 Fig. 6 is a perspective view of the other member of the device.

Referring to the accompanying drawing, and especially to Figs. 1, 2, and 3, 10 represents a portion of the wall at one side of the 50 stairway, 11 the tread of one of the steps thereof, and 12 the riser of the step above. On the steps is laid the carpet 13, which is adapted to be held in place by my improved fasteners which will now be described.

55 The device is generally in the form of a hinge which includes the member 14 and the

member 15 connected by means of the pivot pin 15'.

The member 14 is formed from a single piece of metal and has upturned parallel 60 and apertured wings 16 for the reception of the said pivot pin 15'. The lower ends of these wings are formed with the projections 17 which are adapted to bite into the surface of the wall, tread, or riser, whichever 65 the case may be, where the said member 14 is secured. The other end of the member 14 is formed with a downturned flange 18 which is also adapted to bite into the surface to which the member is attached, and whereby 70 the member is prevented from slipping.

The member 15 is formed with a pair of angularly extending apertured ears 19 which are disposed in parallel relation and arranged inwardly of the wings 16 for the reception of the pivot pin 15'. Between the ears 19 the member 15 is formed with a rolled portion which embraces the intermediate portion of the pin 15', as shown in the drawing, whereby slots 20 are produced between said rolled portion and said ears. Within the rolled portion and encircling the pin 15', is a coil spring 21, one end of which is disposed on one of the slots 20 and bears 75 against the end thereof, while the other end is disposed in the other slot and bears on the face of the member 15. This spring exerts a pressure on the members 14 and 15 whereby they are urged to lie in the same plane. The outer end of the member 15 is formed 80 with an undercut notch 22 to permit the finger of the operator to be inserted beneath the end of said member for the purpose of swinging said member on its pivot to place the edge of the carpet therebeneath or to release the same therefrom.

It will be noted that the first-named end of the coil spring bears against the face of the member 14, when the parts are in the same plane, but rides through the slot 20 100 when the parts are swung against the tension of the spring 21.

As seen in Fig. 1, the member 14 is secured to the wall at the end of the step, at a point immediately above the tread, and close to the riser of the next step above, the member 15 pressing on the carpet and holding the same on the tread of the step. It will be noted that the member 14 is provided with a screw receiving opening 23.

As seen in Fig. 2, the member 14 is secured to the upper face of the tread of the step

close to the riser of the next step above, the members 14 and 15 being in an approximately straight line with the member 15 pressing the carpet firmly down on the tread.

5 In Fig. 3, the member 14 is attached to the wall at the end of the step the member 15 engaging with the carpet to press the same against the vertical face of the riser, at a point close to the tread of the step below.

10 By means of these devices, it being understood that there are two for each step, the use of tacks is obviated, it being only necessary to lift the member 15 on its pivot and place the edge of the carpet therebeneath, 15 after which said member is permitted to press against the carpet, under the influence of the coil spring, to hold the carpet firmly against the step.

Particular attention is called to the fact 20 that the rolled portion of the member 15 forms a casing for the coil spring.

What is claimed is:

1. A stair carpet fastener including a stairway attached member having a biting flange, 25 a second member pivotally connected to the first member, said second member being formed with a pair of apertured ears, the first member having a pair of apertured wings receiving the said ears therebetween, 30 a pivot pin disposed through said ears and wings, the second member being formed with a rolled portion between the ears, a coil spring engaged around the pin and within

said rolled portion, one end of the spring bearing on the first member and the other 35 end bearing on the other member, the said ears having biting projections on their inner ends, the second member being formed with an extension having a corrugated carpet engaging face. 40

2. A stair carpet fastener including a stairway attaching member having means for biting engagement with the stair, a carpet holding member movably connected to the first member, the movably connected portion 45 of the carpet holding member being formed with a pair of parallel apertured ears and a rolled member disposed therebetween and spaced from the ears, the first member having apertured ears engaging outwardly of 50 the second ears and receiving a pivot member therethrough, a coil spring encircling the pivot member within the rolled portion and having one end engaged with the first attaching member between the rolled member 55 and one of the first ears, and its other end engaging the other or carpet holding member between the rolled member and the other first ear.

In testimony whereof, I affix my signature, 60 in the presence of two witnesses.

MILLARD J. COLE.
